UNITED STATES PATENT OFFICE

2,286,163

SWITCH CONSTRUCTION

Newton C. Schellenger, El Paso, Tex., assignor to
Chicago Telephone Supply Company, Elkhart,
Ind., a corporation of Indiana

Original application May 2, 1938, Serial No.
205,399, now Patent No. 2,211,706, dated August
13, 1940. Divided and this application June
17, 1940, Serial No. 340,970

2 Claims. (Cl. 206—67)

This invention relates to electric switches and refers particularly to small switches of the type illustrated in the copending application of Newton C. Schellenger, Serial No. 205,399, filed May 2, 1938, which has matured into Patent No. 2,211,706, patented August 13, 1940, of which this application is a division.

These switches generally comprise spaced stationary contacts mounted on a suitable base of insulating material and adapted to be electrically bridged by a contactor movable across the base. Because of the character of their use, these switches must be capable of satisfactory operation throughout a relatively long period of service involving a great many makes and breaks.

To this end, utmost care is exercised in the design of the switches to insure against mechanical wear, and to minimize destructive arcing effects, the switches are generally of the snap action type.

However, notwithstanding their snap action, one of the most troublesome aspects of the problem of insuring satisfactory operation over a long period of service is contact failure due to pitting and corrosion.

This objection can be reduced materially by keeping the contacts lubricated. It is, therefore, an object of this invention to provide an expedient manner of maintaining a supply of lubricant adjacent to the contacts to be fed thereto as the lubricant on the contacts is burned off in the operation of the switch.

More specifically it is an object of this invention to provide a switch of the character described which incorporates lubricant containing pockets or wells in the base on which the stationary contacts are mounted and also in the switch arm which carries the contactor.

With the above and other objects in view, which will appear as the description proceeds, this invention resides in the novel construction, combination and arrangement of parts substantially as hereinafter described, and more particularly defined by the appended claims, it being understood that such changes in the precise embodiment of the hereindisclosed invention may be made as come within the scope of the claims.

The accompanying drawings illustrate one complete example of the physical embodiment of the invention, constructed in accordance with the best mode so far devised for the practical application of the principles thereof, and in which:

Figure 1 is a rear view of a combined switch and volume control of the type with which this invention is particularly concerned;

Figure 2 is a longitudinal sectional view through the combined switch and volume control;

Figure 3 is a sectional view through Figure 2 on the plane of the line 3—3 illustrating the switch in open position;

Figure 4 is a view similar to Figure 3 but showing the switch closed;

Figure 5 is a detail sectional view through Figure 3 on the plane of the line 5—5; and

Figure 6 is a detail sectional view taken through Figure 3 on the plane of the line 6—6.

Referring now particularly to the accompanying drawings, in which like numerals indicate like parts, the numeral 5 designates generally a switch of the type with which this invention is directly concerned.

As illustrated in Figures 1 and 2, the switch may be mounted on the back of a volume control designated generally by the numeral 6 to be operable by the volume control shaft 7. In the present instance, the switch and volume control combination are of the "doughnut" type wherein the operating shaft passes entirely therethrough.

It is to be understood, however, that the invention is not limited to switch and volume control combinations such as shown, but is applicable to any switch structure of this general class.

Inasmuch as the volume control forms no part of this invention, it has not been specifically illustrated, suffice it to say that the control comprises a base 8 having a resistor 9 mounted thereon. An appropriate contact shoe (not shown) is arranged to traverse the resistor. The contact shoe is carried by a rotatable contact member 10 drivingly connected with the shaft 7 to be operated thereby.

A cup-shaped metal housing 11 positioned over the variable resistor mechanism of the volume control and connected to its base 8 has the switch 5 mounted on its end wall 12. The switch mechanism is enclosed within a suitable housing comprising a flat base 13 of insulating material and a cylindrical metal side wall 14, the enclosure being completed by the wall 12. The base 13 and also the wall 12 are apertured to allow the operating shaft to pass centrally through the switch.

The base 13 mounts two spaced stationary contacts 15 and 16 which are adapted to be electrically bridged by a contactor 17. These stationary contacts consist of the inturned ends of terminal members 18 and 19, respectively. The terminal members are secured to the base by rivets or other fastenings 20, with their inturned

ends passing through correspondingly shaped openings 21 in the insulating base. In this manner the combined terminal members and contacts are secured against rotation about their fastening rivets 20.

The movable contactor 17 consists of a strip of resilient flat stock bent to a substantially serpentine formation which provides spaced contact portions 22 and 23, respectively engageable with the stationary contacts 15 and 16. Between these contact portions, the contactor 17 has an attaching lug 24 projecting from one edge thereof to engage in an opening 25 in a movable switch arm 26.

The opening 25 is somewhat larger than the lug 24 to give the contactor a degree of freedom with respect to the switch arm and allow its contact portions to adjust themselves to their respective stationary contacts, relative motion between the contactor and switch arm being limited by a second lug 27 on one end of the contactor engaging in a notch 28 in the adjacent edge portion of the switch arm.

The switch arm 26 is pivoted on a post 29 secured to the base 13 to oscillate across the base in a switch closing and opening motion. Also pivoted on the post 29 is a switch actuator 30 which is connected with the arm by a spring 31 so that a toggle structure is produced through which the switch arm and consequently the contactor is snapped from one position to the other as the actuator 30 is rocked about the post 29 between its limits of motion. Switch actuating motion is imparted to the actuator by a driving lug 32 movable with the contact member 10 of the volume control.

It is to be observed that the contacts 15 and 16 are so disposed as to cross the paths of the contact portions 22 and 23 at the same angle so that as the switch is closed, the contactor engages the contacts with a wedge-like action. This, together with the resiliency of the contactor and its relatively loose connection with the switch arm, insures good contact and uniform contact pressure at both contacts.

Good contact between the stationary and moving contact surfaces throughout a long period of service, depends, however, upon the maintenance of smooth clean contact surfaces. A slight degree of relative sliding motion between the contacting surfaces is necessary to insure the desired condition; and while the arrangement of the contacts and the resiliency of the contactor go a long way toward insuring this optimum switch action, it has been found that the useful life of the switch can be materially prolonged by maintaining the contact surfaces adequately lubricated.

To this end, the base 13 is provided with lubricant pockets or wells 33 in the form of enlargements of its openings 21 on the inner sides of the contacts 15 and 16. These pockets or wells are filled with a suitable viscous lubricant such as Vaseline during assembly of the switch to provide a reservoir of lubricant directly adjacent to the contacts. The outer ends of these openings

are closed by the flat walls 18' and 19' of the terminal members.

Lubricant reservoirs are also provided adjacent to the contact portions 22 and 23 of the contactor. These reservoirs consist of openings 34 in the switch arm 26 directly adjacent to the contact portions as clearly shown in Figures 3 and 4. The openings 34, like the pockets or wells 33, are filled with viscous lubricant, such as Vaseline.

The close proximity of the lubricant reservoirs to the contacts insures the lubricant working down over the contacts as the lubricant thereon is burned off during operation of the switch.

From the foregoing description taken in connection with the accompanying drawings, it will be readily apparent that this invention provides an improvement in small electric switches of the type used in radio receivers by which the useful life of the switch is materially increased.

20 What I claim as my invention is:

1. In an electric switch: a base of insulating material; a stationary contact member mounted on the base, said contact member having angularly disposed contact and terminal portions the former fitting against the outer face of the base and the latter projecting through a hole in the base and being exposed on the inner face of the base; a contactor movable to and from engagement with the stationary contact member; and means for providing lubricant to the contacting surfaces of the stationary contact member and the contactor comprising, a hole through the base adjacent to the contact portion of the stationary contact and under the terminal portion thereof so that said hole and the terminal portion covering it provide a lubricant reservoir opening to the inner face of the base adjacent to the contact portion, and lubricant in said reservoir.

2. In an electric switch: a base of insulating material; a stationary contact member mounted on the base, said contact member having angularly disposed contact and terminal portions the former fitting against the outer face of the base and the latter projecting through a hole in the base to be exposed at the inner face of the base; means for providing lubricant to the contact portion comprising an enlargement of the hole through which the contact portion projects, said enlargement of the hole being under the terminal portion of the contact member so as to be covered thereby and said hole and terminal portion coact to form a lubricant reservoir bounded at one side by the contact portion, and lubricant in said reservoir; a movable contactor co-operable with the stationary contact member; a carrier for the contactor; means connecting the contactor to the carrier in a manner allowing limited motion of the contactor with respect to the carrier; and means for supplying lubricant to the contact surface of the contactor and between the contactor and the carrier comprising a hole in the carrier adjacent to the contact portion of the contactor, and lubricant in said hole.
